Inventor:

Dagfinn Tossius.

By Morgan & Rubinstein Atty's

UNITED STATES PATENT OFFICE.

DAGFINN LOSSIUS, OF CHICAGO, ILLINOIS.

TOBACCO-PIPE CLEANER.

No. 899,418.

Specification of Letters Patent.

Patented Sept. 22, 1908.

Application filed July 6, 1908. Serial No. 442,113.

To all whom it may concern:

Be it known that I, DAGFINN LOSSIUS, a subject of the King of Norway, and residing at Chicago, county of Cook, and State of Illinois, have invented a new and useful Improvement in Tobacco-Pipe Cleaners, of which the following is a specification:

The object of my invention is to provide a simple and cheap device adapted to be carried on the person, which can be inserted in the bowl of a pipe and by rotating it therein will cut out all matter incrusted therein.

The manner in which I accomplish my object is described in the following specifications and illustrated in the accompanying drawings in which:—

Figure 1 is a side elevation of a pipe, the bowl being in section showing my device inserted therein. Fig. 2 is a horizontal cross section on the line 2—2, Fig. 1. Fig. 3 is a vertical cross section on the line 3—3 Fig. 1 and Fig. 4 are vertical elevations showing the edge of the device.

In the drawings A represents an ordinary pipe and B the interior of the bowl thereof. C indicates the pipe cleaner as a whole. This cleaner consists of a metallic spring loop D, constructed with parallel extensions or legs E; these legs are flat and comparatively thin as compared with the round part F of the loop and are pierced at the ends G for pivot pins H. Pivotally secured to each of the legs E by the pivot pins H are a pair of scrapers I and J. Each of these members have a pair of fixed jaws K between which the legs E of the loop D are pivotally held by the pivot pins H. The face of each of the members I and J are grooved longitudinally to form parallel V shaped edges L. On one of these members I the grooved face is straight and the face of the other member J is curved as shown in Fig. 1. In cross section the grooved face of each of said members is rounded to fit the curve of the interior of the bowl.

When my device is constructed as described and illustrated, its use and operation is as follows: The spring tension of the loop is set with the legs E spaced from each other so as to require pressure to bring the members I and J close enough together for insertion into the bowl of a pipe, and when inserted

therein to press the grooved face of each member against the walls of the interior. This spring pressure also forces the said members to fit any vertical inclination there may be in the said interior as each of said members is pivotally free for such adjustment by the spring pressure. The vertical curved face of the member J is adapted to clean such parts as cannot be reached by the straight face of the member I and to clean out the bottom part of the bowl, and the whole interior being thus scraped clean by the rotation of the cleaner therein.

What I claim and desire to secure by Letters Patent is:

1. A device of the kind described consisting of a looped spring member having a pair of legs; and a pair of members pivotally supported on said legs, each of said members having vertically grooved faces, said members being adapted to be inserted in the bowl of a tobacco pipe and by rotation therein to scrape and thereby clean the interior thereof.

2. In a device of the kind described, the combination with a spring member having a loop and a pair of legs; of a pair of longitudinally grooved members pivotally secured to the end of said legs, said members when pivotally attached to said spring member, being insertible in the bowl of a tobacco pipe and by rotation therein are adapted to clean the interior thereof.

3. In a device of the kind described, the combination with a spring member; of a pair of longitudinally grooved members, said members being pivotally secured to opposite parts of said spring member and insertible in the bowl of a tobacco pipe, the grooved parts of said members being in contact with and adapted when said device is rotated, to scrape and thereby clean said bowl.

4. In a device of the kind described, the combination with a spring member, of a pair of members pivotally secured to said spring member, each of said pair of members having a grooved face adapted when inserted in the bowl of a tobacco pipe and rotated to scrape and clean the interior thereof.

DAGFINN LOSSIUS.
